(57) **CLAIM**

The ornamental design for a food vessel, as shown and described.

DESCRIPTION

FIG. 1 is a front elevation view of a food vessel, the rear being a mirror image;

FIG. 2 is a left side elevation view of the food vessel of FIG. 1, the right side being a mirror image;

FIG. 3 is a top view of the food vessel of FIG. 1; and, FIG. 4 is a bottom view of the food vessel of FIG. 1.

The broken lines illustrate environmental structure and form no part of the claimed design.
